UNITED STATES PATENT OFFICE.

ADRIANO ARIANI, OF NEW YORK, N. Y.

SOSTENUTO MECHANISM FOR PIANOS.

1,224,437.

Specification of Letters Patent.

Patented May 1, 1917.

Application filed July 6, 1914. Serial No. 849,096.

To all whom it may concern:

Be it known that I, ADRIANO ARIANI, a subject of the King of Italy, residing in the borough of Manhattan, city, county, and State of New York, have invented certain new and useful Improvements in Sostenuto Mechanism for Pianos, of which the following is a specification.

This invention relates to sostenuto mechanism for pianos and like instruments.

An object of this invention is to provide mechanism under the control of the performer for positioning in sustained position the damper or dampers of the string or strings corresponding to the tone or tones desired to be sustained and for retaining at will the damper positioning means in sustained position and independently of the "loud" pedal of the piano or other string instrument, and preferably by the provision of means whereby the normal "touch" of the key-board is fully preserved. In the usual preferred forms of my invention, the sostenuto pedal imparts a predetermined movement to a sostenuto frame carrying striking devices adapted to strike positioning elements corresponding respectively to the keys of the key-board and thereby position in sustained position the corresponding damper of any key desired to be sustained, said striking devices being arranged to be individually operated by actuating members individually controlled by the respective keys. In the more preferred forms of my invention, the actuation of the damper positioning means is effected at a time instant in advance of the time instant at which the sostenuto frame reaches its terminal position.

By my invention, the "loud" pedal may be operated to secure the desired fortissimo effects subsequent or prior to the operation of the sostenuto mechanism, and upon the release of said "loud" pedal while the sostenuto pedal is still held in operated position, the sostenuto mechanism will not be affected in any way and solely the desired tone or tones will be sustained. Furthermore, my invention secures the improved advantage that upon proper subsequent operation of the sostenuto mechanism subsequent to the striking of the keys corresponding to the tones desired to be sustained, the action of all other keys with respect to the hammers, dampers, etc., will not be disturbed or interfered with, thereby fully preserving the normal operation of such other keys and

not affecting in the slightest degree the "touch" of the same.

Other features and advantages will be more fully understood from the following description and the accompanying drawings, in which—

Figure 1 is a diagrammatic sectional elevation showing one embodiment of my invention; the parts of my sostenuto mechanism and the ordinary parts of the piano corresponding to a single key being shown in neutral position;

Fig. 2 is a sectional elevation similar to Fig. 1 indicating the sostenuto mechanism in "sustained" position and causing the damper of the string corresponding to the "struck" key to be held in raised position;

Fig. 3 is a detail perspective view of the frame of certain parts of the sostenuto mechanism indicated in the preceding figures;

Fig. 4 is a diagram illustrating the operation of my sostenuto mechanism by means of a sostenuto pedal; and Fig. 5 is a detail sectional view.

Referring to the drawings, the hammer 1 is operated by the key 2 by the usual operating means, the type of piano action illustrated being that of a grand piano. The damper 3 of key 2 is controlled thereby through the intermediation of the damper lever 4 and damper rod 5. These parts and such other parts necessary for securing their operation are of the usual construction and need not be more specifically referred to herein.

The sostenuto mechanism constituting my invention comprises the actuating member 6, shown carried by the key 2, and it will be understood that each key is similarly provided with such actuating member 6. In suitable relation to the members 6 of the keys is provided the sostenuto frame 7, shown as constituted of the forward rail 8 and rearward rail 9, (Fig. 3) and transverse partition members 10. These partition members 10 form compartments corresponding to the respective keys of the key-board, and within each compartment is pivotally or otherwise movably suspended a striking device 11, shown as having the head-piece 12 and tail-piece 13. Each striking device 11 is provided adjacent the end of its tail-piece 13 with the tripping element 14 projecting beyond tail-piece 13. Preferably, the tripping element 14 is pivotally carried by tail-piece 13, as by means of the wire frame 15, see

Fig. 5—to permit the return movement of tripping element 14 without affecting the position of striking device 11 relative to the frame 7.

5 In the drawings, I have indicated an ordinary damper or "loud" pedal arrangement, such as is shown in the United States Patent No. 164,052, Steinway, granted June 1, 1875, comprising the rail 40 exposed to the action 10 of the damper pedal acting on the rod 41.

The frame 7 is guided by any suitable guiding means, such as the set of guide projections or strips 16, 17, carried by the opposite sides of the piano case, and the movement 15 of frame 7 in the opposite sets of guide strips 16, 17, may be controlled by a sostenuto pedal 18, as for example, by the link 19, bell crank 20 and link 21. The frame 7 may be returned to neutral position by means 20 of the spring 22 having one end secured at any suitable fixed point 23 and its other end connected to the lever 24 in turn connected to link 21 by means of link 25.

Suitably positioned with respect to each 25 striking device 11 for the corresponding keys and wires there is provided damper positioning mechanism, shown as comprising oscillating stops 30, respectively corresponding to the keys of the key-board and 30 shown respectively pivotally supported on individual studs within individual compartments of the fixed bar 31, the sides of each compartment frictionally holding the oscillating stop therein positioned in normal or 35 upright position. Each damper rod 5 is provided with a catch-piece 32, preferably adjustably positioned thereon as by adjusting screws 33, 33, and each catch-piece 32 is provided with the recess 34 coöoperating with 40 the head 35 of the corresponding stop 30. The compartments for the several stops 30 are shown as formed from a strip of wood or similar material which is cut away excepting at the part indicated as hatched in 45 the drawings; however, it will be clear that such compartments may be formed by means of a strip having the construction indicated by the said hatched portion and spaced partitions projecting from said portion at 50 proper intervals. The bar 31 may be supported by the sides of the piano case in any suitable manner.

We will assume that the key 2 indicated 55 in the drawings has been struck, thereby causing the corresponding hammer 1 to strike the corresponding string 36, and also to effect the raising of the corresponding damper 3 by means of the damper lever 4 and damper rod 5. Upon operation of the 60 sostenuto pedal 18 at the proper instant, the frame 7 will be moved to the left, as viewed in the drawings, and the tripping element 14 will encounter the projecting portion of actuating member 6, as indicated 65 in Fig. 2. Upon continued movement of

frame 7 in such left hand direction, the striking device 11 will be oscillated to the position indicated by the dotted lines, thereby causing stop 30 to be oscillated in the direction of arrow 37. Upon release of the key 2, the damper 3 and catch piece 32 will descend to a point at which the head 35 of stop 30 will engage the upper wall of recess 34, whereupon the damper 3 will be held in sustained position, as shown in Fig. 70 2. In the interim, the frame 7 under action 75 of the sostenuto pedal 18 will have continued its movement to its terminal position indicated in full lines in Fig. 2, and the tripping element 14 will be free from engagement with the actuating member 6. The pad 38 of felt or like material is provided to deaden the rebound of striking piece 11 after 80 striking the stop 30. For simplification, we will assume that the tone corresponding to the indicated key 2 is the sole tone desired to be sustained. During such operation of the frame 7 from its neutral position indicated in Fig. 1 to the "terminal" position 85 indicated in Fig. 2, the striking devices 11 of all other keys will have been moved without affecting their respective stops 30, and accordingly the damper 3 of the key 2 will be the only damper in raised position. It will be noted that in movement of the striking devices 11 of the other keys, no interference whatever will take place between the stops 30 of such other keys and the remaining parts of the sostenuto mechanism. It will be further noted that when the frame 90 100 95 105 110 115 120 125 130 135 140 145 150 155 160 165 170 175 180 185 190 195 200 205 210 215 220 225 230 235 240 245 250 255 260 265 270 275 280 10185 10190 10195 10200 10205 10210 10215 10220 10225 10230 10235 10240 10245 10250 10255 10260 10265 10270 10275 10280 10285 10290 10295 10300

one side flat and the other side curved, the flat side being on the left of the several figures, also to provide the free end of actuating member 6 with a similar "point" the flat side being on the right hand of the several figures. Such "points" secure the advantages of insuring the proper actuation of the striking device or devices corresponding to the tone or tones desired to be sustained, while 10 permitting freedom of movement of the striking device of any key which may have been struck soon after the striking of the keys corresponding to the sustained tones.

It will be noted that the recess 34 is so shaped that the damper rod 5 may be raised under action of the "loud" pedal, without disturbing the stop 30; accordingly, when the "loud" pedal is released while the sostenuto pedal is still held in operative position, 20 the stop 30 will again engage the upper wall of recess 34, holding damper 3 away from the string 36, thereby still preserving the sustained effect of the tone corresponding to the string 36.

25 Each operated damper stop 30 is returned to neutral position by the action of the forward rail 8 encountering the base of such operated damper stop 30 upon the return movement of frame 7 under action of the 30 spring 22, as above described.

Whereas I have illustrated my invention in relation to a grand piano, it will be understood that similar sostenuto mechanism may be provided for upright and other types of 35 pianos to maintain the dampers away from the strings corresponding to the tones desired to be sustained. It will be understood that the members 6 need not be carried directly by the respective keys, but may be 40 otherwise suitably controlled to be moved into proper position relative to the striking devices upon movement of the keys.

From the foregoing, it will be clear that 45 my sostenuto mechanism is entirely independent of the "loud" pedal, and that the operation of my sostenuto mechanism does not affect in any way the "touch" nor the normal operation of the piano action.

Whereas I have illustrated my invention 50 by reference to specific forms thereof, it will be clear that many changes and modifications may be made without departing from my invention.

What I claim and desire to secure by Letters Patent is:—

1. The combination with a key operated string instrument having dampers for the strings, of sostenuto mechanism comprising a movable support, guides for said support, means for imparting movement to said support, striking devices mounted on said support, damper stops mounted to be moved respectively by said striking devices and means controlled by the keys for actuating 65 said striking devices.

2. The combination with a key operated string instrument having dampers for the strings, of sostenuto mechanism comprising a support movable along a predetermined path, guides for said support, means for moving said support along said guides, striking devices movably mounted on said support, damper stops mounted to be moved respectively by said striking devices, and means controlled by the keys for individually actuating said striking devices. 70

3. The combination with a key-operated string instrument having dampers for the strings, of sostenuto mechanism comprising a support movable along a predetermined path, striking devices movably mounted on said support, damper stops mounted to be moved respectively by said striking devices, means for mounting said damper stops, means for moving said support along said predetermined path and means controlled by the respective keys for actuating corresponding striking devices when said movable support passes an intermediate position of its path. 80

4. The combination with a key operated string instrument having dampers for the strings, of sostenuto mechanism comprising a movable support, means for moving said support, striking devices, means for mounting said striking devices on said support to effect rotational movement, damper stops mounted to be respectively moved by said striking devices and means individually controlled by the keys for individually actuating the corresponding striking devices. 90

5. The combination with a key operated string instrument having dampers for the strings, of sostenuto mechanism comprising a movable support, means for moving said support along a predetermined path, striking devices, means for mounting said striking devices on said support to effect rotational movement, damper stops mounted to be respectively moved by said striking devices, and means individually controlled by the keys for individually actuating said striking devices when said support passes an intermediate point along said predetermined path. 100

6. The combination with a key operated string instrument having dampers for the strings, of sostenuto mechanism comprising a movable support, means for moving said support along a predetermined path, striking devices, means for pivotally mounting said striking devices on said support, damper stops mounted to be respectively moved by said striking devices, and means individually controlled by the keys for respectively actuating said striking devices. 110

7. The combination with a key operated string instrument having dampers for the strings, of sostenuto mechanism comprising a sostenuto rail, means for moving said rail, 120

fixed guides for guiding the movement of said rail along a predetermined path, striking devices mounted side by side on said rail, damper stops arranged side by side of 5 one another, pivotal mounting means for said damper stops and means individually controlled by keys for respectively actuating said striking devices.

8. The combination with a key operated 10 string instrument having dampers for the strings, of sostenuto mechanism comprising a sostenuto rail, means for moving said rail, fixed means for guiding said rail along a predetermined path, striking devices, means 15 for pivotally suspending said striking devices on said rail, damper stops corresponding to said striking devices, means for mounting said damper stops respectively above said striking devices and means controlled respectively by the keys for actuating 20 said striking devices disposed respectively below said striking devices.

9. The combination with a key operated string instrument having dampers for the 25 strings, of sostenuto mechanism comprising a sostenuto rail, means for bodily moving said sostenuto rail, striking devices provided with individual means for holding the same in normal position, means for pivotally 30 mounting said striking devices side-by-side on said sostenuto rail, and damper stops actuated by said striking devices.

10. The combination with a key operated string instrument having dampers for the 35 strings, of sostenuto mechanism comprising a sostenuto rail, means for bodily moving said sostenuto rail in a predetermined direction, striking devices provided with individual counter-weighting means, means for 40 pivotally mounting said striking devices on said sostenuto rail, and damper stops respectively actuated by said striking devices.

11. The combination with a key operated string instrument having dampers and damper stops for the strings, of a sostenuto rail, striking devices for effecting the movement of said damper stops, said striking devices being movably mounted on said rail, said striking devices respectively having individual projecting portions and means for 50 pivotally mounting said projecting portions respectively on said striking devices.

12. The combination with a key operated string instrument having dampers and 55 damper stops for the strings, of a sostenuto

rail, striking devices for effecting the movement of said damper stops, said striking devices being movably mounted on said rail, said striking devices respectively having an enlarged counterweighting portion and a lower projecting portion and means for pivotally mounting said projecting portions respectively on said striking devices.

13. The combination with a plurality of 65 keys and dampers and damper stops corresponding thereto, of a sostenuto rail, means for moving said rail, striking devices respectively effecting the movement of said damper stops, said striking devices being movably mounted on said rail and actuating 70 members individually controlled by said keys and mounted to respectively engage said striking devices upon movement of said rail.

14. The combination with a plurality of 75 keys and dampers and damper stops corresponding thereto, of a sostenuto rail, means for moving said rail, striking devices respectively effecting the movement of said 80 damper stops, said striking devices being movably mounted on said rail, actuating members individually controlled by said keys and means controlling said striking devices and arranged to be respectively engaged by said actuating means upon movement of said sostenuto rail in a certain direction, said controlling means being ineffective upon the movement of said rail in another direction.

15. The combination with a plurality of 90 keys, dampers and damper stops, of a sostenuto rail, means for moving said rail, striking devices respectively effecting the movement of said damper stops, said striking devices being movably mounted on said rail, 95 actuating members respectively carried by said keys and means respectively carried by said striking devices for moving said striking devices upon movement of said sostenuto rail in a certain direction, said controlling 100 means being ineffective upon movement of said sostenuto rail in the opposite direction.

In testimony whereof I have signed this specification in the presence of two subscribing witnesses.

ADRIANO ARIANI.
